UNITED STATES PATENT OFFICE.

JOHN EDWIN TULL, OF BROOKLYN, NEW YORK.

WATER-CIRCULATOR FOR STEAM-BOILERS.

1,109,882.

Specification of Letters Patent.

Patented Sept. 8, 1914.

Application filed July 31, 1913. Serial No. 782,367.

To all whom it may concern:

Be it known that I, JOHN EDWIN TULL, a citizen of the United States, residing at Brooklyn, in the county of Kings and State of New York, have invented certain new and useful Improvements in Water-Circulators for Steam-Boilers, of which the following is a specification.

The principal object of the invention is to promote the rapid circulation of the water and to rapidly equalize the temperature of the various parts of the boiler whereby is avoided the danger resulting from unequal expansion of the boiler owing to varying temperatures in the bottom and upper parts thereof.

My invention therefore consists in the means, hereinafter described and finally claimed, for effecting a rapid, continuous, and complete circulation of the water so that the same is maintained at a substantially uniform or even temperature.

The nature, characteristic features and scope of the invention will more readily be understood from the following description taken in connection with the accompanying drawings, forming a part hereof, wherein—

Figure 1 is a view with the head removed of a well-known type of marine boiler embodying my improvements. Fig. 2 is a longitudinal sectional view of the same. Fig. 3 is a sectional-elevational view of the circulator and the turbine or means for driving it; and Fig. 4 is a central vertical sectional view of the circulator and turbine.

Referring to the drawings, the numeral 1 represents the shell of a well-known type of marine boiler; 2 are the furnace flues; 3 are the return tubes through which the heated products pass; and 4 are stay bolts.

The circulator 5 and its motor or turbine 6 are mounted within the boiler a little below the water level and may be carried on a common base or support, such as the casting 45 7. The latter is secured by chairs 8 depending from two adjoining stay bolts.

The turbine may be of any appropriate design. That shown in the drawings embodies a common type of rotor or bucket design vice mounted on a shaft 9 within a suitable shell or casing 10, the inlet 11 of which connects with the feed pump (not shown) by means of a pipe 12.

The circulator is illustrated in the form

of a centrifugal or suction pump consisting 55 of a shaft 13 and radial blades or pistons 14, which coöperate with an appropriate housing 15, having an inlet 16 and an outlet or delivery part 17.

Connected with the inlet 16 are suction 60 pipes 18, extending to the bottom of the boiler and equipped with perforate terminals 19. It is evident that when the pump is operating the dead water will be drawn from the bottom of the boiler and discharged by the pump at the top so that there is a constant and rapid circulation of the water and a substantially uniform or even temperature.

Motion is transmitted to the circulator by 70 a gear wheel 20 on the turbine shaft, which meshes with a pinion 21 on the circulator shaft.

It will be obvious to those skilled in the art to which the invention relates that modifications may be made in details without departing from the spirit and scope thereof. Hence the invention is not limited other than required by the state of the prior art.

Having described the nature and object 80 of the invention I claim:

1. The combination with a steam boiler, of a turbine operated by the feed water supply, and means operated by the turbine for drawing the dead water from the bottom of 85 the boiler and discharging it at the top thereof.

2. The combination with a steam boiler, of a suction pump for drawing the dead water from the bottom of the boiler and discharging it at the top thereof, and means responsive to feed water pressure for driving said pump.

3. The combination with a steam boiler having an internal furnace, of an inter-gearred turbine and suction pump, a feed water pipe connected with the inlet of the turbine, and suction pipes extending from the pump to the bottom of the boiler.

4. The combination with a steam boiler 100 having an internal furnace, of a water circulator and its complemental motor mounted on a common base, and chairs to support said base.

5. The combination with a steam boiler 105 having an internal furnace, of a suction pump mounted in the boiler a little below the water level and having suction pipes ex-

tending to the bottom of the boiler and equipped with perforate terminals, and means for driving said pump in response to feed water pressure.

5 6. The combination with a steam boiler having stay bolts, of a water circulator and a feed water driven motor mounted on a common base, and chairs depending from

the stay bolts and adapted and arranged to carry said base.

10 In testimony whereof I affix my signature in presence of two witnesses.

JOHN EDWIN TULL.

Witnesses:
